CONDIMENT CONTAINER OR SIMILAR ARTICLE

Phillip J. Mesi, Chicago, Ill., assignor to Tote-brush, Inc., Chicago, Ill., a corporation of Illinois

Application April 27, 1950, Serial No. 9,520

Term of patent 7 years

(Cl. D44—22)

To all whom it may concern:

Be it known, that I, Phillip J. Mesi, a citizen of the United States, residing at Chicago, in the county of Cook and State of Illinois, have invented a new, original, and ornamental Design for a Condiment Container or Similar Article, of which the following is a specification, reference being had to the accompanying drawing, forming a part thereof, in which:

Fig. 1 is a perspective view of a condiment container, showing my new design; and

Fig. 2 is another perspective view thereof with the parts disassembled for use.

I claim:

The ornamental design for a condiment container or similar article, substantially as shown.

PHILLIP J. MESI.
